Primary Examiner — Karen E Eldridge Powers

(57) CLAIM

The ornamental design for a handle for toothbrush, as shown and described.

DESCRIPTION

FIG. 1 is a perspective view showing my design; FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines in FIG. 7 illustrate features of the handle for toothbrush that form no part of the claimed design.
